(57) **CLAIM**

The ornamental design for an automatically self-cleaning pet potty, as shown and described.

DESCRIPTION

FIG. 1 is a left side front perspective view for an automatically self-cleaning pet potty;

FIG. 2 is a right side front perspective view thereof;

FIG. 3 is a left side rear perspective view thereof;

FIG. 4 is a right side rear perspective view thereof;

FIG. 5 is a left side view thereof;

FIG. 6 is a right side view thereof;

FIG. 7 is a rear view thereof;

FIG. 8 is a front view thereof;

FIG. 9 is a top view thereof; and,

FIG. 10 is a bottom view thereof.

The broken lines in the drawings are for illustrative purposes only and form no part of the claimed design.

1 Claim, 5 Drawing Sheets
